ROLLER SKATE CLAMP

Irving Jaffee, New York, N. Y.

Application March 5, 1935, Serial No. 9,358

6 Claims. (Cl. 280—11.32)

This invention relates to skates and more particularly to a new and improved toe clamp particularly adapted for use on roller skates, although it will be understood that my invention is not limited thereto and may be used for other purposes, as for instance on ice skates.

As is well known, roller skates are usually provided with an adjustable clamp arranged to embrace the shoe sole of the wearer at the toe portion of the shoe. As such clamps are ordinarily constructed it is difficult to get a satisfactory engagement between the clamp and the edge of the shoe, because the clamp does not conform to the curvature of the shoe sole and 15 engages the sole only at one point instead of throughout the entire width of the clamp. This results in unnecessary injury to the shoe and is also dangerous.

It has also been suggested that the outer portion of the clamp might be swiveled to permit the clamp to make better contact with the shoe. Such clamps, however, are not satisfactory because of the difficulty in properly adjusting them. This is particularly dangerous in the case of 25 children who may not understand the necessity for careful adjustment and in affixing the skate may believe that it is firmly attached whereas, as a matter of fact, it is not.

Attempts to use a skate under such conditions are likely to result in falls with attendant injury. One reason for this difficulty is that in the case of a swivel clamp the freedom of motion allows the clamp to slide longitudinally of the shoe, shifting its position. Since children's 30 shoes are customarily made very broad at the toe and have little curvature in the radius of attachment of the clamp, it requires careful adjustment of such clamps to secure the skate firmly and securely in position and many children are incapable of doing so.

It is an object of this invention to provide a 35 skate clamp which will conform to the curvature of the shoe sole, which will engage the sole firmly and tenaciously without injury to it, with reduced likelihood of working loose and which is so constructed and arranged as to limit the swiveling movement of the outer portion of the clamp within such limits that while the clamp may adjust itself through a sufficient amount to engage the shoe sole firmly and without likelihood of accidentally slipping off, it nevertheless cannot swing so far in either direction as to permit longitudinal slipping of the shoe in the skate even though the skate has been carelessly or 45 quickly applied.

Still other objects and advantages of my invention will be apparent from the specification.

The features of novelty which I believe to be characteristic of my invention are set forth with 50 particularity in the appended claims. My in-

vention itself, both as to its fundamental principles and as to its particular embodiments will best be understood by reference to the specification and accompanying drawing, in which

Fig. 1 is a top plan view of a skate with a 5 clamp according to my invention mounted thereon;

Fig. 2 is a side elevation, partly in section, of the same;

Fig. 3 is a bottom plan view thereof; 10

Fig. 4 is a top plan view of a modified form of a clamp according to my invention;

Fig. 5 is a bottom plan thereof;

Fig. 6 is a side elevational view partly in section; 15 and

Fig. 7 is a fragmentary vertical section on the line 1—7 of Fig. 1.

Referring now more particularly to Fig. 1, 1 designates the sole of the skate at the toe portion. Secured to the sole I have indicated the extremities 2 of the structure which carries the front 20 wheels. Since the mounting and arrangement of the wheel structure forms per se no part of my invention the same is shown only in diagrammatic form.

Projecting downwardly from the under side of the sole from the position of the toe clamp, there is provided an arm 3 bifurcated at its lower extremity to provide spaced portions 3a and 3b. The narrowed upper end of this arm may be 30 passed through the sole portion and its upper extremity headed over. For the purpose of adjusting the width of the clamp there is provided the bolt having oppositely threaded portions 4a and 4b and a central portion of reduced diameter 5 fitting into the bifurcated arm 3. One 35 end of the bolt may be provided with a squared portion to receive a wrench.

The left and right clamps comprise horizontally extending portions 6a and 6b having downturned inner portions 7a and 7b provided with a threaded hole engaging the threaded portions 4a and 4b. The horizontal portion may be adjustably secured on the skate by means of a downturned flange on each edge of the sole as 45 8a and 8b at the forward side, 9a and 9b at the rear side, having inwardly faced notches 10 and 11 to receive the horizontal portions 6a and 6b. Thus by rotating the bolt the clamps will move 50 inwardly and outwardly, depending on the direction of rotation.

The sole engaging portion 12a and 12b is an L-shaped piece preferably pivotally secured on the sliding portion by rivets 13a and 13b and the upstanding portion is preferably bent inwardly 55 slightly at the top as at 14a and 14b and notches may be provided on opposite edges of the clamp as at 15b to receive a band of elastics 16a and 16b.

Thus it will be seen that the sole engaging 60

portion may swing through an arc upon the horizontal portion. For the purpose of limiting this movement I may extend the horizontal portion inwardly on a taper as at 18a and 18b so that at the desired limit of forward movement of the outside of the clamp, the tapered portion strikes against the forward face of the plates 9a and 9b, as indicated by the dotted lines in Fig. 3.

The limit of movement in the other direction is preferably provided by cutting away the outer extremity of the horizontal portion at an angle outwardly to the rear as at 17a and 17b so that at the limit of rearward movement the outermost part of the horizontal portion engages the vertical portion of the sole engaging part, as indicated by the position of the left-hand clamp in Fig. 3.

It will be understood, however, that the plates 8a and 8b may serve to limit the backward movement of the clamp, if desired, but in this instance it would be necessary to extend them further to the rear and I prefer to utilize the contact between the outer and inner portions of the clamp for providing the rear stop.

Referring now more particularly to Figs. 4, 5 and 6, I have shown a modified form of clamp secured to the skate in a somewhat different manner. In this instance no down-turned flanges may be provided on the skate sole, but there may be instead rivets 20a and 20b extending downwardly from the sole of the skate and having an enlarged lower head spaced from the sole of the skate by a distance sufficient to permit the horizontal portion of the clamp, each of which is provided with slots 21a and 21b respectively, to be held against the sole of the skate thereby. The general formation of the horizontal portion of the clamp and of the sole engaging portion is otherwise similar to that already described with the exception that the sole engaging portion in this instance is pivoted at the rear outward extremity of the horizontal portion of the clamp and the pivoted portion is not provided with the inwardly extending arm as before.

In this instance 22a and 22b designate the rivets about which the outer portion of the clamp is swingable and, as before, the faces 23a and 23b project outwardly to the rear, and the rear extremity contacting with the vertical face of the sole engaging portion forms a stop limiting the rearward movement. In this instance it may be desirable to increase the angle at which the outer ends of the horizontal portions are cut away and if desired the configuration of the edges 23a and 23b may be made such that the striking of the vertical portion against the forward edge constitutes a stop limiting the forward motion.

While I have shown and described certain preferred embodiments of my invention it will be understood that modifications and changes may be made without departing from the spirit and scope thereof, as will be clear to those skilled in the art.

I claim:

1. In a skate clamp, in combination, a pair of transverse clamping members secured to the under side of the sole of the skate for transverse sliding movement, threaded means for driving said clamping members, a pair of L-shaped shoe-engaging clamps respectively mounted to swivel upon the external part of said transverse mem-

bers, each transverse member and cooperating L-shaped clamp having portions arranged to engage each other at a predetermined angular position of said L-shaped clamp, whereby the backward movement of said swiveled L-shaped clamp is limited. 5

2. In a skate clamp, in combination, a pair of transverse clamping members secured to the under side of the sole of the skate for transverse sliding movement, threaded means for driving 10 said clamping members, a pair of L-shaped shoe-engaging clamps respectively swiveled upon the external part of said transverse members, each transverse member and cooperating L-shaped clamp having portions arranged to strike to limit 15 the backward movement of said L-shaped clamp, the vertical sole-engaging portion of said clamp having a narrowed zone to position an elastic for contact with the shoe sole.

3. In a skate clamp, in combination, a pair of transverse clamping members secured to the under side of the sole of the skate for transverse sliding movement, threaded means for driving 20 said clamping members, a pair of L-shaped shoe-engaging clamps respectively mounted to swivel 25 upon the external part of said transverse members, and means for limiting the turning movement of said clamp in either direction to less than 90°.

4. In a skate clamp, in combination, a pair of transverse clamping members secured to the under side of the sole of the skate for transverse sliding movement, threaded means for driving 30 said clamping members, a pair of L-shaped shoe-engaging clamps swiveled upon the external part 35 of said transverse members, said L-shaped clamps and said transverse members having portions arranged to strike to limit the backward movement of the clamp, and said L-shaped clamp having a projection beyond the pivot arranged to 40 strike an abutment to limit the forward movement of the clamp.

5. In a skate clamp, in combination, a pair of transverse clamping members secured to the under side of the sole of the skate for transverse 45 sliding movement, and having a longitudinal slot therein, the forward outer ends of said transverse members being cut away, a pair of L-shaped shoe-engaging clamps respectively swiveled upon the rear outer extremity of said transverse members, said L-shaped clamps and said transverse members having portions arranged to strike to 50 limit the backward movement of the said L-shaped clamps.

6. In a skate clamp, in combination, a pair of transverse clamping members secured to the under side of the sole of the skate for transverse sliding movement, threaded means for driving 55 said clamping members, a pair of L-shaped shoe-engaging clamps swiveled upon the external part 60 of said transverse members, the vertical portion of each shoe-engaging clamp having a reduced width intermediate its ends and a band of buffer material surrounding said reduced portion, said transverse members and said L-shaped clamps 65 having portions arranged to engage each other at a predetermined angular position of said L-shaped clamp, whereby the backward movement of said L-shaped clamps is limited.

IRVING JAFFEE.
